UNITED STATES PATENT OFFICE.

THOMAS ELLIOTT, OF CINCINNATI, OHIO.

GUARD FOR THE WINDOWS OF PASSENGER-CARS.

1,148,012.

Specification of Letters Patent. Patented July 27, 1915.

Application filed February 3, 1915. Serial No. 5,947.

To all whom it may concern:

Be it known that I, THOMAS ELLIOTT, a citizen of the United States, and a resident of Cincinnati, in the county of Hamilton, 5 and State of Ohio, have invented certain new and useful Improvements in Guards for the Windows of Passenger-Cars; and I do hereby declare the following to be a full, clear, and exact description of the invention, 10 such as will enable others skilled in the art to which it appertains to make and use the same.

My invention relates to an improvement in guards for the windows of passenger cars, 15 the object being to provide simple and strong means for detachably securing the guards or grating to the outer sides of the window frame and which will permit of the quick removal of the guards when it is necessary 20 to get at the windows for any purpose from the outside.

With these objects in view my invention consists in the parts and combination of 25 parts as will be more fully described and pointed out in the claims.

In the accompanying drawings, Figure 1 is a view in elevation of a car showing my improvement applied thereto; Fig. 2 is an enlarged view showing the manner of 30 securing the guard or grating in place; Fig. 3 is a view in section; Fig. 4 is a view of one of the end brackets for the upper end of the grating; Fig. 5 is a similar view of one of the brackets used intermediate the ends; 35 Fig. 6 is a view of the clamp for the lower end of the end bars of the guards or grating and Fig. 7 is a view in section of same.

The guards or grating are located at the outer sides of the windows and close up to 40 the same and are for the purpose of lessening accidents by preventing passengers from putting their arms or heads out of the windows. These guards should be removable so as to enable the windows to be glazed and 45 cleaned from the outside, and my invention provides means for detachably securing them in place so that they may be readily removed and replaced.

The guards are made up in sections, each 50 of which may be composed of a series of parallel horizontal rods 2 connected at their ends, and at intermediate points by the vertical bars 3, as shown, or they may be composed of the end and intermediate bars with 55 rods 2 at the top and bottom, and a wire or other screen or grating closing the space

bounded by the rods and bars. Each guard or grating, is designed to span a plurality of windows and the vertical bars 3 are located to come between the windows so as to engage 60 the supports.

Secured to the side posts or other part of the car frame intermediate the windows are the brackets 4, and at the extreme ends or beyond the windows to be protected by the 65 guard, are the brackets 5. Each of the brackets 4 and 5 is provided with two separated parallel ears 6. Both ears of the bracket 4, are provided with downwardly and rearwardly inclined slots 7, which are 70 of a size sufficient to receive the top rod 2 of the guard section, and the side ears are separated sufficiently to receive between them the abutting bars 3 of two adjacent guard sections, while the ears of the brackets intermediate the ends of the guard sections receive a single bar 3, but are separated sufficiently to receive two so as to be interchangeable.

The end brackets 5 are each provided with 80 two ears only one of which is slotted to receive the top rod 2 of the guard, the solid outer ears acting simply as abutments to prevent any longitudinal movement of the guard section and also to add a finish to the 85 end of the guard. The brackets are, as above explained, secured to the side posts or frame between the windows and also at the ends beyond the windows to be protected, and operate by the inclination of the slots, which 90 is upwardly and outwardly and by the shoulders 7^a to absolutely prevent sufficient outward movement of the upper ends of the guard sections, to disconnect the guard section from the brackets 4 or 5. 95

Located under each bracket, and in a position to support and clamp the lower ends of the vertical bars 3 of the guard sections, are the combined supports and clamps 8. These supports and clamps each comprise a 100 supporting member having a horizontal seat or shoulder 9 intermediate its ends, and a spring controlled clamp 10 pivoted to the supporting member adjacent said seat and adapted to engage the front faces of the 105 bars 3, just above the lower ends of the latter. Each supporting member is hollowed out and open at the rear for the reception of a spring or springs 12, and is provided immediately below the seat or shoulder 9 with 110 the bearings 13 open at the rear, to receive the cross bar 11 of the clamp 10, the cross

bar 11 being provided with an integral tongue 14 against which the upper ends of the springs 12 bear. The clamp 10 projects upwardly slightly above the supporting seat 5 or shoulder 9 and straddles the same, and is normally retained with its upper free end 15 over said shoulder by the spring. The lower ends of the bars 3 rest on the seats or shoulders 9, while the clamps 10 bear against 10 the outer edges of said bars and yieldingly hold them against outward displacement.

With the upper rods 2 within the downwardly and rearwardly inclined slots in the upper brackets 4 and 5, and the lower ends 15 of the bars 3 resting on the fixed seats or shoulders 9, it will be seen that the guard sections cannot be removed except by moving the lower edges outwardly, which is prevented by the clamps. With the clamps 20 shown, the leverage obtainable is so short, that they cannot be moved outwardly by any ordinary pressure exerted on the guards, but may be moved to release the guard sections by grasping their upper ends and pulling outwardly on same thus permitting the 25 lower ends of the bars to be moved outwardly, after which the section is free to be removed from the upper brackets.

With the construction as shown, if the 30 guards be lifted the upper ends of the end bars 3 will engage the shoulders 7^a before the top rod 2 leaves slot 7, and before the lower end of bars 3 are in a plane above the clamps 10, hence in order to release the 35 guards, the clamps 10 must first be forced downwardly thus permitting the lower ends of the guards to be pulled outwardly, after which the top rods 2 may be removed from the slots or the guards may be simply turned up out of the way, thus giving free access to the lower part of the window sash and frame.

With this construction, the several sections of the guard or grating are independent of the others and any one section may be removed without disturbing any of the others and may be readily removed and re-

placed by one person, without the use of any tools or the employment of any detachable devices that are liable to be lost or 50 mislaid.

It is evident that many slight changes might be resorted to in the relative arrangement of parts shown and described without departing from the spirit and scope of my 55 invention. Hence I would have it understood that I do not wish to confine myself to the exact construction and arrangement of parts shown and described, but

Having fully described my invention 60 what I claim as new and desire to secure by Letters-Patent, is:—

1. The combination with parallel ears separated to receive the end bars of two adjacent guard sections between them, the said ears being slotted, supporting seats below said ears, guard sections having parts to enter the slots in the ears, and end bars, the adjacent end bars of two guard sections resting 65 between the ears of one pair and also upon the supporting seat below said ears, and means engaging said bars above and adjacent the seats for locking the guards in place.

2. The combination with brackets each 75 having parallel ears separated to receive the end bars of two adjacent sections between them, the said ears being slotted, supporting seats below said brackets, guard sections having parts to enter the slots in the ears, 80 and end bars, the adjacent end bars of two guard sections resting between the ears of each bracket, and also upon the supporting seat below said back and spring clamps carried by said seats and engaging the end 85 bars, for locking the latter on the seats.

In testimony whereof, I have signed this specification in the presence of two subscribing witnesses.

THOMAS ELLIOTT.
